UNITED STATES PATENT OFFICE.

WILLIAM ORR, OF TRENTON, NEW JERSEY, ASSIGNOR TO THE NEW JERSEY WIRE CLOTH COMPANY, OF SAME PLACE.

FIREPROOF CONSTRUCTION.

SPECIFICATION forming part of Letters Patent No. 644,939, dated March 6, 1900.

Application filed August 6, 1898. Serial No. 687,926. (No model.)

To all whom it may concern:

Be it known that I, WILLIAM ORR, a citizen of the United States, residing at Trenton, county of Mercer, and State of New Jersey, have invented certain new and useful Improvements in Fireproof Constructions, fully described and represented in the following specification and the accompanying drawings, forming a part of the same.

10 This invention relates to fireproof floor and ceiling constructions, the object of the invention being to provide an improved construction of this class securing the desired fireproof qualities with a comparatively-small 15 amount of concrete and with a ceiling properly supported by hangers in such manner that the fireproofing of the webs and lower flanges of the beams and the means for supporting the ceiling may be conveniently and 20 rapidly applied.

As a full understanding of the invention can best be given by a detailed description of constructions embodying the same, such a description will now be given in connection 25 with the accompanying drawings, illustrating all the features of the invention as applied in preferred forms in fireproof floor and ceiling constructions, and the features forming the invention will then be specifically pointed 30 out in the claims.

In the drawings, Figure 1 is a vertical section of a fireproof floor and ceiling construction, taken transversely to the I-beams, one of the beam-protecting blocks in each pair 35 being shown in elevation and the other in section. Fig. 2 is a section of the same parallel with the beam. Figs. 3, 4, and 5 are partial views similar to Fig. 1, showing modified arrangements of the ceiling-hangers.

40 Referring to said drawings, A A are two adjacent beams of the common I form, the webs and lower flanges of which are fireproofed by blocks of molded fireproof material applied to opposite sides of the beams and 45 resting upon the lower flanges of the latter, these blocks preferably extending, as shown, beneath the flanges of the beams, so as to form fireproofing on the under side of the latter, as 50 well as along the webs, although this is not essential to the invention broadly considered.

Upon the tops of the blocks B rest the ends

of metal joists C, extending from beam to beam and which are preferably metal plates placed edgewise vertically and spaced at the proper distances apart. They may be used 55 without spanners or with spanners of any suitable form. As shown, the spanners x consist of metal rods provided with hooks at opposite ends which take over the top edges of two adjacent joists, so as to hold the latter 60 in vertical position and assure the uniform spacing of the joists. Below the joists C and preferably supported therefrom is reticulated metal D, which may be of any suitable form and size of openings between the parts and 65 of woven or netted wire, or metal plates or rods, or perforated or expanded sheet metal, or any other form of reticulated metal, but is shown as common wire lathing, this lathing being shown as secured to and supported 70 from the joists C by wire ties 1 at suitable intervals, although any other suitable means may be used. A filling of concrete or similar plastic material is applied from above, so as to embed the joists C and secure the tensile 75 strength of the joists and lathing and fill the space above the lathing D to the tops of the beams, thus fireproofing the upper portions of the beams and forming a fireproof floor- 80 upon which the board or other suitable floor- 85 G, as shown.

Referring now to the ceiling construction, a feature of the invention consists in the use 85 of hangers which are carried or held in position on the beam-flanges by the blocks B and extend below the beam protection 2, formed by the portions of the blocks beneath the beams, so as to support the ceiling below this beam protection, and either with or without 90 an air-space between the two. The hangers are preferably molded into the blocks, so as to form a single structure therewith; but the invention includes also a construction in which the hangers are lapped over the flanges 95 of the beams and held in position by the blocks, in which case the blocks are preferably chambered out, so as to accommodate the hangers and hold them in position, although the blocks rest directly upon the flanges of the beams at 100 other points.

In the construction shown in Fig. 1 the

hangers a are molded into the blocks B , so as to be carried thereby, and are preferably formed with bent ends adapted to overlap the flanges of the beams and are molded in such 5 a position in the blocks as to rest upon the flanges of the beams when the blocks are in place, the other ends of the hangers a projecting downward through the beam protection 2 of the blocks and below the latter to 10 the desired distance, according as to whether or not an air-space is to be formed between the ceiling and beam protection and the amount of air-space desired. In the construction shown the hangers a extend but slightly below 15 the beam protection 2 and are provided at their lower ends with eyes 3, through which extend the supporting tension-rods H for the ceiling, which are secured in proper position under tension by the nuts 4, as usual in such 20 constructions, and on which rods H the metallic lathing I of any suitable form is supported, being shown as secured thereto by wire ties 5, this metallic lathing carrying the usual plaster ceiling J . This ceiling construction, consisting of the rods H , wire lathing I , and plaster J , is of a common construction, and it will be understood that the features of the invention may be used with a 25 ceiling construction of any other suitable 30 form supported by the hangers a .

The form and position of the hangers a , carried by the blocks B , may be varied widely from that shown in Fig. 1. In Fig. 3 I have shown a construction in which the hangers a' are molded into the blocks and have bent 35 ends taking over the flanges of the beams in the same manner as shown in Fig. 1, but the vertical portions of the hangers, by which the ceiling is dropped from the blocks, are outside 40 the blocks instead of extending through the beam protection 2, as shown in Fig. 1.

In Fig. 4 I have shown a construction similar to that shown in Fig. 1, with the hangers a^2 molded into the blocks, but not having 45 their ends bent so as to take over the flanges of the beams, the hangers in this construction extending through the beam protection 2 and then upward past the flanges of the beams through the body of the blocks.

50 While I preferably mold the hangers into the blocks, as shown in Figs. 1 to 4, so that the blocks and hangers form a single construction, as this construction is more convenient and efficient, enabling the ceiling to be constructed more rapidly, this part of the invention, broadly considered, also includes hangers held in position by blocks of fireproof material forming the beam protection, although not molded therein. Such a construction 55 is shown in Fig. 5, in which the hangers a^3 consist of rods bent so as to hook around the flanges of the beams and form a vertical portion extending downward centrally of the beam between the two parts of the beam-protection 2 formed by the blocks B on opposite sides of the beam, the blocks B in this construction being provided with grooves 6, in

which the portions of the hangers a^3 within the blocks are inclosed when the blocks are in place.

70 It will be understood by those skilled in the art that many modifications may be made in the construction shown without departing from the invention and that the features of the invention that relate to the fireproof floor 75 and ceiling support may be used independently of each other and are thus claimed, although they are preferably used together, and thus form a complete floor and ceiling construction, which forms a part of the invention.

80 What I claim is—

1. The combination with flanged beams, of fireproof blocks arranged on opposite sides of the webs of the beams and resting upon the 85 flanges of the beams, metal joists supported on the tops of the blocks and extending from beam to beam, reticulated metal extending from beam to beam and between the joists, and a filling of concrete or similar plastic material 90 applied upon said reticulated metal, substantially as described.

2. The combination with flanged beams, of fireproof blocks arranged on opposite sides of the webs of the beams and resting upon the 95 flanges of the beams, metal joists supported on the tops of the blocks and extending from beam to beam, reticulated metal supported by and below said joists, and a filling of concrete or similar plastic material applied upon 100 said reticulated metal and in which the joists and portions of the beams above the blocks are embedded, substantially as described.

3. The combination with flanged beams, of fireproof blocks extending along the webs of 105 the beams and below the beams to form a fireproof protection for the webs and bottoms of the beams and resting upon the flanges of the beams, joists supported on the tops of the blocks and extending from beam to beam, reticulated metal below said joists, and a filling of concrete or similar plastic material applied upon 110 said reticulated metal and in which the joists and portions of the beams above the blocks are embedded, substantially as described.

4. The combination with flanged beams, of fireproof blocks extending along the webs of 115 the beams and below the beams to form a fireproof protection for the webs and bottoms of 120 the beams, joists supported on the tops of the blocks and extending from beam to beam, reticulated metal extending from beam to beam and between the joists, a filling of concrete or similar plastic material above said reticulated metal, hangers held in position on the beams by the blocks and extending below the protection beneath the beams, and a ceiling supported by said hangers, substantially as 125 described.

5. The combination with flanged beams, of a fireproof floor including a framework of reticulated metal covering the space between the beams and a filling of concrete or similar 130

plastic material applied from above upon said reticulated metal, and fireproof blocks on opposite sides of the webs of the beams resting upon the flanges of the beams and forming substantially the sole support for the fireproof floor, substantially as described.

6. The combination with flanged beams, of fireproof blocks arranged on opposite sides of the webs of the beams and resting upon the flanges of the beams, a framework of reticulated metal covering the space between the beams and supported on the tops of the blocks, a filling of concrete or similar plastic material applied on said reticulated metal, hangers 15 consisting of metal rods or strips molded into said blocks and projecting below the beams, and a ceiling supported by said hangers, substantially as described.

7. A fireproof block formed of plastic material molded to the required form to rest upon the lower flange of a beam and extend beneath the beam to form a fireproof protection for the bottom of the beam and having molded therein a ceiling-hanger formed of a metal rod or strip having one end bent to overlap and rest upon the flange of the beam when the block is applied thereto and its other end projecting from the block to support a ceiling below the latter, substantially as described.

In testimony whereof I have hereunto set my hand in the presence of two subscribing witnesses.

WILLIAM ORR.
